UNITED STATES PATENT OFFICE

OLAF HALVORSEN, OF CHICAGO, ILLINOIS

DESIGN FOR A BILLFOLD OR SIMILAR ARTICLE OF MANUFACTURE

Application filed August 18, 1931. Serial No. 40,878. Term of patent 3½ years.

To all whom it may concern:

Be it known that I, OLAF HALVORSEN, a citizen of the United States, residing at Chicago, in the county of Cook and State of Illinois, have invented a new, original, and ornamental Design for a Billfold or Similar Article of Manufacture, of which the following is a specification, reference being had to the accompanying drawings, forming part thereof.

Fig. 1 is a plan view of a bill-fold showing my design; and Fig. 2 is an edge elevational view of a bill-fold showing my design.

I claim:

The ornamental design for a billfold or similar article of manufacture, substantially as shown.

OLAF HALVORSEN.
